UNITED STATES PATENT OFFICE.

HENRY WEBER, OF CHICAGO, ILLINOIS, ASSIGNOR TO LATHAM MACHINERY COMPANY, OF CHICAGO, ILLINOIS, A CORPORATION OF ILLINOIS.

STAPLING-MACHINE FOR BOXES, CASES, AND THE LIKE.

1,111,113.

Specification of Letters Patent. Patented Sept. 22, 1914.

Application filed February 1, 1910. Serial No. 541,208.

To all whom it may concern:

Be it known that I, HENRY WEBER, a citizen of the United States, residing at Chicago, in the county of Cook and State of Illinois, have invented certain new and useful Improvements in Stapling-Machines for Boxes, Cases, and the like, of which the following is a specification.

In the manufacture of boxes, tubular cases, and the like, one of the edges of the box or case is generally provided with a flap which projects beyond the edge and rests against the face of the wall adjacent another edge, and the edges are secured together by stitching or inserting a fastening staple through the flap and the adjacent wall of the box. With stapling machines as now constructed, it is only possible to insert the staple in close proximity to the corner of the case, or midway between the edges of the flap, and as these flaps vary in width, it will be apparent that an extended free edge will be produced by the flap, and which edge will not be secured down against the face of the wall, and will cause considerable inconvenience to the user.

In order to overcome these difficulties and objections, and to provide an improved machine of this character, which is capable of being adjusted to any desired angle with respect to the work to insert the staple at any desired angle with respect to the grain of the work and according to the width of the flap to secure the free edge thereof against the adjacent wall of the box, thereby producing a much stronger joint is the primary object of the present invention.

A further object is to provide an improved machine of this character in which the stapling mechanism may be rigidly adjusted to any angle with respect to the work, and improved means for securing the mechanism in its adjusted positions.

A further object is to provide an improved work support co-operating with the stapling mechanism, and improved means for correspondingly and independently adjusting such support with respect to the stitching mechanism.

50 A further object is to provide improved means for securing the work support in any of its adjusted positions.

A further object is to provide an improved machine of this character which will be

simple, durable and cheap in construction and effective and efficient in operation.

To the attainment of these ends and the accomplishment of other new and useful objects, as will appear, the invention consists in the features of novelty in the construction, combination and arrangement of the several parts hereinafter more fully described and claimed, and shown in the accompanying drawings illustrating an embodiment of the invention, and in which—

Figure 1 is a side elevation of an improved machine of this character constructed in accordance with the principles of this invention. Fig. 2 is an enlarged detail sectional view of the head and the operating and adjusting mechanisms of the stitcher. Fig. 3 is a sectional view on line 3—3 of Fig. 2. Fig. 4 is a sectional view on line 4—4 of Fig. 2. Fig. 5 is a view similar to Fig. 4, showing the stitching mechanism in an adjusted position with respect to the main support. Fig. 6 is an enlarged detail view partly in section showing the means for securing the stitching mechanism in any of its adjusted positions. Fig. 7 is a detail sectional view taken on line 7—7 of Fig. 1. Fig. 8 is an enlarged detail sectional view taken on line 8—8 of Fig. 7. Fig. 9 is a detail sectional view taken on line 9—9 of Fig. 7. Fig. 10 is an enlarged detail view partly in section of the locking mechanism for securing the work support in any of its adjusted positions. Fig. 11 is a diagram showing staples inserted in the work at various angles to the edge of the work.

Referring more particularly to the drawings, and in the present exemplification of the invention, the numeral 15 designates a main support which is provided with an arm 16 having a head 17 at the free end thereof. This head 17 is provided with a recess 18 upon the front thereof, as shown more clearly in Fig. 2. The stapling or stitching mechanism designated generally by the reference numeral 19 in Fig. 1, may be of any desired or well known construction, and preferably comprises a staple former 20, a driver 21 and a cam 22 for operating the former and driver. The cam is provided with a cam groove 23 which receives a projection 24 on the former 20. Connected to the driver 21 is a link 25, and this link in turn has a fixed connection 26 with the cam.

The stitching mechanism is mounted upon a shiftable support 26, which is preferably provided with spaced projecting arms or extensions 27, 28, and these extensions are adapted to be inserted into the recess 18 in the head 17 through the open side thereof. An axle or pivot pin 29 is provided, which passes through the top and bottom of the head 17, and also through the extensions 28, 29 of the support 26. One extremity of the pivot pin or axle 29 is secured to the lower wall of the recess 18, preferably by means of threads 30 on said extremity. The portion of the pivot pin which passes through the wall of the recess is preferably smooth and enlarged as at 31, to form a shoulder 32. The pivot pin or axle 29 projects beyond one of the walls of the recess in the head, preferably the upper wall, and is provided with an operating wheel or handle 33, by means of which the pivot pin or axle may be rotated, and when rotated, the threaded extremity 30 will cause the same to be simultaneously and longitudinally adjusted. A bevel gear 34 is loosely supported upon the pin or axle 29, and is arranged to rotate about the latter in a horizontal plane. This gear 34 is supported by means of a collar 35 which cooperates with the shoulder 32 and between which the gear is held. The cam 22 is provided with an axle 36 which extends through the support 26 and projects into the recess 18 of the head 17. The free end of the axle 36 may be supported in any desired or suitable manner, but is preferably journaled in a bearing 37 on the extension 28. A bevel gear 38 is secured to the axle 36, preferably between the support 26 and the bearing 37, and is arranged so that the gear 34 will mesh therewith. A power shaft 39 is journaled by one extremity in the head 17, and by the other extremity preferably in a portion of the arm 16. A bevel gear 40 is secured to the free end of the shaft and is located within the recess 18 to rotate in an upright plane, and so arranged that the gear 34 will mesh therewith. Motion may be imparted to the shaft 39 in any desired or suitable manner, preferably by means of the pulley 41, and a clutch mechanism designated generally by the reference numeral 42, may be provided for locking the pulley to the shaft. This clutch mechanism is controlled by a treadle 43 located in a convenient place for the operator, and through the mechanism of connecting links 44, 45 and lever 46. The stapling mechanism being mounted upon the support 26, and the latter being rotatable about the pivot or axle 29 on an upright axis, may be adjusted to any desired angle about the axis, and with respect to the head 17. In order to impart such adjustment to the stapling mechanism, the gear 34 must be moved from the position

with the gears 38, 40 and into the position shown in dotted lines in said figure. This adjustment may be accomplished by means of the handle 33 to rotate the pivot or axle 29, and when thus adjusted, the stapling mechanism and support 26 may be turned about its pivot from the position shown in Fig. 4 to the position shown in Fig. 5, or to an intermediate position, after which the pivot or axle may be adjusted in the opposite direction, and the gear 34 moved into mesh with the gears 38, 40.

Any suitable means may be provided for securing the stitching or stapling mechanism in its adjusted position, and for this purpose one of the projecting portions of the support 26 may be provided with a plurality of apertures 47. A fastening pin or bolt 48 is provided with a threaded body portion and this portion passes through one of the walls of the recess 18, and is provided with a handle 49, by means of which it may be longitudinally adjusted. The free extremity of the bolt 48 is preferably smooth, as shown at 50 in Fig. 6, and is adapted to be moved into or out of any one of the apertures or recesses 47 on the extension 28, so that in order to adjust the stitching mechanism about its pivot the extremity 50 of the bolt 48 must be withdrawn from the aperture 47, the mechanism adjusted, and when adjusted the extremity of the bolt inserted in another of the apertures.

By providing the adjustable gear 34 it will be apparent that the stitching mechanism may be adjusted about its pivot without varying the stroke of the staple forming mechanism, that is, without altering the timing of the operation of the cam 22. It will be apparent that should the gear 34 be allowed to remain in mesh with the gears 38 and 40 during this rotative adjustment of the stitching mechanism, the cam 22 would be operated during the adjustment, so as to vary the time of operation thereof. By moving the gear 34 out of mesh with the gears 38, 40 before adjustment, the timing of the operation of the cam 22 will be uniform in any of the adjusted positions of the stitching mechanism.

If desired, one side of the head 17 may be left open and a suitable closure 51 may be provided by means of which ready access may be had to the gearing in the recess 18. This closure may be secured to the head by means of hinges 52 and an elastic member 53^a may be provided, which tends normally to hold the closure closed.

In order to ascertain the adjustment of the stitching mechanism and to properly position the same any suitable means may be provided, such as a catch comprising graduations or indications 53, which may be marked upon any suitable portion of the mechanism, preferably upon the front of

one of the walls of the recess 18, as shown more clearly in Fig. 3, and a pointer or indicator 54 may be supported by any movable part of the mechanism, preferably the support 26, to coöperate with the graduations or indications. These graduations 53 and the indicator 54 are so arranged that when the indicator is adjacent any one of the graduations, one of the apertures 47 in the extension 28 of the support 26 will be properly positioned to receive the extremity 50 of the bolt 48.

The work is supported by means of a work support which preferably comprises an arm 55 having a narrow supporting surface. This arm is pivotally mounted, as at 56, for adjustment in an upright plane to a suitable bracket or support 57, and this bracket or support is mounted for lateral adjustment upon a lateral extension 58, which is formed upon or secured to the main support 15 below the arm 16. Any suitable means may be provided for forming the connection between the bracket 57 and the extension 58, and for this purpose the extension may be provided with grooves 59, within which the heads of the bolts or fastening devices 60 are adapted to slide. These bolts or fastening devices pass through the base 61 of the brackets 57 for securing the parts together. The work support 55 may be adjusted about its horizontal axis or pivot in any desired or suitable manner, preferably by means of an adjusting device or screw 62 (see Fig. 1), which passes through the extension 63 of the support 55, and has engagement with the face 64 on the base 61 of the brackets. The support 53 is adapted to be adjusted laterally with respect to the main support 15, and for this purpose the extension 58 is preferably provided with ears or bearings 65 which project beyond the faces thereof and between which bearings or ears the base 61 of the brackets 57 is located. An adjusting screw 66 is journaled by its extremities in these ears or projections 65 and passes through and has threaded engagement with the arms of the bracket 57 and an operating handle or crank 67 is secured by one extremity to the screw. The screw is held against longitudinal adjustment by means of securing devices 68 in the form of nuts or collars secured to the free extremity of the screw. With this construction it will be apparent that when the handle 67 is operated to rotate the screw 66, the latter will by its threaded engagement with the bracket supporting the work support 53, adjust the bracket and support laterally with respect to the main support 15 from the position shown in Fig. 7 in full lines to that shown in dotted lines, or to an intermediate position.

65 Any suitable means may be provided for

locking the work support in its adjusted positions, and for this purpose there may be provided a latch or catch 69 which is pivotally mounted, as at 70, upon a fixed support, preferably the extension 58. A pin 71 is provided which passes through the free extremity of the latch and projects beyond the lower face thereof. The projecting portion of this pin coöperates with and is adapted to enter the apertures or recesses 72 in the base 61 of the brackets 57, so that when the work support has been adjusted to its desired position, the pin will enter one of the recesses 72 to secure the support against further adjustment. When it is desired to adjust the support, the latch is first moved about its pivot, and the support adjusted, after which the latch or catch may be placed in position so that the pin will enter the adjacent recess.

The work support is provided upon its supporting surface with clenching portions 73, and these portions 73 are so arranged that one of the portions will coöperate with the staple forming and driving mechanism in each of the positions of the latter, that is to say, when the staple forming or driving mechanism is in the position shown in Fig. 4 the foremost of the portions 73 will coöperate therewith to clench the staple. When the stapling mechanism is in the position shown in Fig. 5, the rearmost portion of the portion 73 will coöperate therewith after the work support has been laterally positioned to the position shown in Fig. 7, to clench the staple. Should the stapling mechanism be adjusted to a position intermediate the positions shown in Figs. 4 and 5, and the work support 53 correspondingly adjusted, the intermediate portion 73 will coöperate with the stitching mechanism to clench the staple.

With this improved construction, it will be apparent that the staple may be inserted through the flap at any desired angle, or in any of the positions shown in diagram in Fig. 11. This mechanism permits the staple to be inserted at any angle at the will of the operator, and according to the grain in the work, so that if a narrow flap is provided, the staple may be inserted lengthwise of the grain, and if a broad flap is provided, it may be inserted cross-wise. If desired, and if the conditions permit, or it is advisable, the staple may be inserted at an angle, that is, in a position to extend obliquely across the grain.

While in the present exemplification of the invention, the mechanism is shown and is designed to insert the staple only in three positions, it is to be understood that provision may be made to adjust the mechanism so as to insert the staple at any desired angle without departing from the spirit of this invention.

In order that the invention might be fully understood, the details of the foregoing embodiment thereof have been thus specifically described, but what is claimed as new is:

5. 1. The combination with a work support, of a stapling mechanism, a driving mechanism coöperating therewith, means for adjusting said stapling mechanism at various angles to said driving mechanism, at the same time maintaining the timing of said stapling mechanism aforesaid, and means for adjusting said work support to align the same with the stapling mechanism in its adjusted positions.
10. 2. The combination of a main support, a work support adjustably mounted on the main support, stapling mechanism mounted upon the main support for adjustment about an upright axis to vary the angle at which the staples are driven to the edge of the work, and means for adjusting the work support transversely with respect to the axis of movement of the stapling mechanism.
15. 3. The combination of a main support, a work support adjustably mounted on the main support, stapling mechanism mounted upon the main support for adjustment about an upright axis to vary the angle of the staple to the edge of the work, means for adjusting the work support transversely with respect to the axis of movement of the stapling mechanism, and means for locking the work support in any of its adjusted positions.
20. 4. The combination of a work support, a stapling mechanism coöperating therewith, means whereby the angle of the staple to the edge of the work may be varied, means including meshing gears for operating the stapling mechanism, a housing inclosing said gears, means outside of the housing for shifting one of the gears out of engagement with the other of said gears to render said operating mechanism inoperative during the adjustment of the stapling mechanism, and means accessible from the outside of the housing for securing the stapling mechanism in any of its adjusted positions.
25. 5. The combination of a stapling mechanism, means whereby the angle of the staple to the edge of the work may be varied, means including meshing gears for operating the stapling mechanism, means for shifting one of the gears out of engagement with the other gear to render said operating mechanism inoperative during the adjustment of the stapling mechanism, and means for securing the stapling mechanism in its adjusted position.
30. 6. In a device of the character described, the combination of a support, stapling mechanism mounted thereon for adjustment about an upright pivot, driving mechanism for the stapling mechanism including spaced
- gears and an intermediate gear meshing with said spaced gears, means for shifting the said intermediate gear out of engagement with the spaced gears to permit the pivotal adjustment of the stapling mechanism, and means for securing the stapling mechanism in its adjusted position.
35. 7. In a device of the character described, the combination of a support, stapling mechanism mounted thereon for adjustment about an upright pivot, driving mechanism for the stapling mechanism including spaced gears and an intermediate gear meshing with said spaced gears, a housing inclosing the gears, means accessible from the outside of the housing for shifting the said intermediate gear out of engagement with the spaced gears to permit the pivotal adjustment of the stapling mechanism, and an indicator for positioning the said mechanism.
40. 8. In a machine of the character described, the combination of a support, stapling mechanism mounted upon the support for movement about an upright pivot, a gear operatively connected with the stapling mechanism and shiftable therewith, a gear spaced from the first mentioned gear toward and away from which the said first mentioned gear is movable when the stapling mechanism is moved about its pivot, a gear meshing with the aforesaid gears and movable out of mesh therewith, means for thus moving said last mentioned gear to permit the stapling mechanism to be adjusted, means for rotating one of the gears and positive means for locking the stapling mechanism in any of its adjusted positions.
45. 9. In a machine of the character described, the combination of a support, stapling mechanism, a pivot pin connecting the said mechanism to the support for adjustment with respect thereto about an upright pivot, a gear operatively connected to the stapling mechanism and shiftable therewith, a fixed gear spaced from the first mentioned gear and with respect to which the said first mentioned gear is shiftable, a gear loosely journaled on the pivot pin and meshing with both of the other said gears, and means for longitudinally shifting the pivot pin to move the gear thereon into and out of mesh with the other gears.
50. 10. In a machine of the character described, the combination of a support, stapling mechanism, a pivot pin connecting the said mechanism to the support for adjustment with respect thereto about an upright pivot, a gear operatively connected to the stapling mechanism and shiftable therewith, a fixed gear spaced from the first mentioned gear and with respect to which the said first mentioned gear is shiftable, a gear loosely journaled on the pivot pin and meshing with both of the other said gears, means for longitudinally shifting the pivot pin to

move the gear thereon into and out of mesh with the other gears, and means for locking the stapling mechanism in its adjusted positions.

5 11. In a machine of the character described, the combination of a support, stapling mechanism, a pivot pin connecting the said mechanism to the support for adjustment with respect thereto about an upright pivot, a gear operatively connected to the stapling mechanism and shiftable therewith, a fixed gear spaced from the first mentioned gear and with respect to which the said first mentioned gear is shiftable, a gear 70
10 loosely journaled on the pivot pin and meshing with both of the other said gears, and means for longitudinally shifting the pivot pin to move the gear thereon into and out of mesh with the other gears, said support 75
15 being provided with a housing within which the gears are located.

12. In a machine of the character described, the combination of a support, stapling mechanism, a pivot pin connecting the said mechanism to the support for adjustment with respect thereto about an upright pivot, a gear operatively connected to the stapling mechanism and shiftable therewith, a fixed gear spaced from the first mentioned gear and with respect to which the said first mentioned gear is shiftable, a gear 80
20 loosely journaled on the pivot pin and meshing with both of the other said gears, means for longitudinally shifting the pivot pin to move the gear thereon into and out of mesh with the other gears, said support 85
25 being provided with a housing within which the gears are located, said housing being provided with an opening through which access may 90
30 be had to the gears, and a closure for the 95
35 opening.

13. In a machine of the character described, the combination of a support provided with a chamber, stapling mechanism, 100
40 a gear operatively connected to the mechanism and located within the chamber, a second gear also within the chamber and spaced from the first gear, a pivot pin connecting the stapling mechanism with the support for 105
45 pivotal adjustment about an upright axis, said pin extending into the chamber with one end projecting outside of the chamber, a gear loosely mounted on the pivot pin, and meshing with the first said gears, a handle 110
50 on the projecting end of the pivot pin for longitudinally adjusting the pin to move the gear thereon into and out of mesh with the first said gears, and means for rotating one of the gears.

30 14. In a machine of the character described, the combination of a support provided with a chamber, stapling mechanism, a gear operatively connected to the mechanism and located within the chamber, a second gear also within the chamber and spaced 115
35

from the first gear, a pivot pin connecting the stapling mechanism with the support for pivotal adjustment about an upright axis, said pin extending into the chamber with one end projecting outside of the chamber, 70
40 a gear loosely mounted on the pivot pin, and meshing with the first said gears, a handle on the projecting end of the pivot pin for longitudinally adjusting the pin to move the gear thereon into and out of mesh with the first said gears, means for rotating one of the gears, and a fastening device accessible from the outside of the housing for securing the stapling mechanism in its adjusted position. 75
80

15. In a machine of the character described, the combination of a support provided with a recess opening through the face thereof, stapling mechanism, a support for the mechanism, said support projecting into the recess, a pivot pin engaging the walls of the recess and passing through the second said support for pivotally connecting the stapling mechanism for pivotal adjustment with respect to the first said support, a gear 85
90 operatively connected to the stapling mechanism and journaled upon the second said support and located within the recess, a second gear also in the recess and spaced from the first gear, a gear supported by the pivot pin within the recess and meshing with the other said gears, means for shifting the gear on the pivot out of mesh with the other gears to permit adjustment of the stapling mechanism and into mesh with the gears again, and means accessible from the outside 95
100 of the recess adapted to engage the second said support to lock the parts in their adjusted positions. 105

16. In a machine of the character described, the combination of a support provided with a recess opening through the face thereof, stapling mechanism, a support for the mechanism, said support projecting into the recess, a pivot pin engaging the walls 105
110 of the recess and passing through the second said support for pivotally connecting the stapling mechanism for pivotal adjustment with respect to the first said support, a gear operatively connected to the stapling mechanism and journaled upon the second said support and located within the recess, a second gear also in the recess and spaced from the first gear, a gear supported by the pivot pin within the recess and meshing with the other said gears, means for shifting the gear on the pivot out of mesh with the other gears to permit adjustment of the stapling mechanism and into mesh with the gears again, the second said support being provided with an opening therein, and a fastening pin accessible from the outside of the recess and adapted to be inserted in the opening to lock the stapling mechanism in 115
120 position. 125
130

17. The combination of a main support, a work support mounted thereon and for pivotal movement in an upright plane, means for bodily adjusting the work support in a horizontal plane, means for locking the work support in its bodily adjusted positions, stapling mechanism mounted upon the main support, and means whereby the angle of the staple to the edge of the work may be varied.
18. The combination of a main support, a work support, means connecting the work support and the main support for lateral adjustment of the support, means engaging both supports and operable to adjust the work support laterally, a catch connected to a fixed support and arranged to engage the work support for locking the latter in its adjusted positions, stapling mechanism co-operating with the work support, and means whereby the angle of the staple to the work edge may be varied.
19. The combination of a main support, a work support, means connecting the work support with the main support for lateral adjustment, a catch connected to a fixed support and arranged to engage the work support for locking the latter in its adjusted positions, stapling mechanism co-operating with the work support and means whereby the angle of the staple to the work edge may be varied.
20. The combination of a main support, a work support, means connecting the work support with the main support for lateral adjustment, means engaging both supports and operable to adjust the work support laterally, a catch pivoted to a fixed support and arranged to engage the work support for locking the latter in its adjusted positions, stapling mechanism co-operating with the work support, and means whereby the angle of the staple to the edge of the work may be varied.
21. The combination of a main support, a work support mounted thereon and for lateral adjustment, means engaging both supports and operable to adjust the work support laterally, a catch pivoted to a fixed support and having a projecting portion, a portion of the work support being provided with openings arranged to receive the projecting portion of the catch to lock the support in its adjusted positions, stapling mechanism mounted upon the main support, and means whereby the angle of the staple to the edge of the work may be varied.
22. The combination of a main support, a work support adjustably mounted thereon and provided with a plurality of staple clenching portions, stapling mechanism mounted on the main support, means whereby the angle of the staple to the edge of the work may be varied, and means whereby the work support may be correspondingly adjusted to position one of said clenching portions to co-operate with the stapling mechanism in each of the positions of the latter.
23. The combination of a main support, a work support, stapling mechanism mounted upon the main support for pivotal adjustment about an upright axis whereby the angle of the staple to the edge of the work may be varied, said work support being provided with a plurality of clenching portions, and means for adjusting the work support and in a direction transversely of the said pivot of the stapling mechanism to position one of the said clenching portions thereon to co-operate with the stapling mechanism in each of its adjusted positions.

In testimony whereof I have signed my name to this specification, in the presence of two subscribing witnesses, on this 14th day of January A. D. 1910.

HENRY WEBER.
